UNITED STATES PATENT OFFICE.

DURWARD M. ALLEN, OF BINGHAMTON, NEW YORK, ASSIGNOR OF ONE-HALF TO
FRANK N. GILBERT, OF BINGHAMTON, NEW YORK.

MOP FOR BASEBOARDS.

Application filed July 14, 1924. Serial No. 725,920.

This invention relates to improvements in mops, and more particularly to a novel mop for use in washing, brushing or cleaning the base boards of walls.

5 The primary object of the invention is to provide a mop consisting of a mop head adapted to be held in a substantially vertical position while it is moved along the floor adjacent to the base board to be brushed or 10 cleaned, the mop head being provided at one or both of its side edges with jaws to adjustably hold the mopping material. Wheels or the like are arranged at the lower edge of the head for carrying the latter as it is 15 moved over the floor by the operator.

With the foregoing object outlined, and with other objects in view which will appear as the description proceeds, the invention consists in the novel features hereinafter described in detail, illustrated in the accompanying drawing, and more particularly pointed out in the appended claims.

Referring to the drawing,

Fig. 1 is a perspective view of one embodiment of the invention shown in use against the base board of a wall.

Fig. 2 is a horizontal sectional view of the same.

Fig. 3 is a rear elevation.

30 Fig. 4 is a side view.

Fig. 5 is a rear elevation of another embodiment of my improved mop.

Fig. 6 is a side edge view of the same.

Fig. 7 is an edge view of a handle bracket 35 forming part of said mop.

Fig. 8 is a rear elevation of the mop.

Fig. 9 is a top plan view of the same.

In the embodiment of the invention illustrated in Figs. 1 to 4, inclusive, A designates the mop head provided at its side edges with metal jaws 3 which are secured to the head by rivets 4' and may be adjusted by means of bolts and thumb nuts 4. These jaws hold the mop material 11 or the wiping element 12.

A handle 5' has a fitting 5'' at one end which is pivotally connected to ears 6, projecting from a plate 7 which may be secured to the mop head by any suitable means.

50 A bracket 8 is fixed to the mop head in any suitable manner and provided with an arc shaped slot 8' to receive a bolt 9 carried by a sleeve 5 arranged on the handle. This bolt may be adjusted in the slot to vary the 55 angle of the handle relatively to the mop

head, and the bolt may be locked in position by the thumb nut 10.

A supporting roller y is arranged at the lower edge of the mop head for supporting the latter as it is moved along the floor adjacent to the base board to be brushed or cleaned.

A cap B may be fitted over the upper edge of the head to vary the exposed portion of the mop material 11 or the wiping element 12. This cap may be adjusted upwardly and downwardly.

In the modification shown in Figs. 5 to 9, inclusive, A designates the mop head which is preferably formed of a metal sheet having its side edges bent to form stationary jaws 3. These jaws cooperate with yielding jaws 3', which are connected to the plate by spring hinges 21. Suitable mop material, (not shown) may be placed between the jaws 70 and be held by the latter, and each yielding jaw is provided with tongues or handles 22, to be used by the operator in manipulating the movable jaws.

The lower edge of the mop head is provided with rollers 20 to carry the mop head as it is moved over the floor by the operator.

A handle bracket C of sheet metal is secured to the rear face of the mop head by any suitable means, and it carries a pivotally mounted handle socket 5, to which the mop handle 5' is connected. The handle 5' may be adjusted laterally on the bracket C, and may be fixed in its adjusted positions by means of a pin 18 which engages one or the other of the holes 18' in the bracket C. The pin 18 is connected to the mop head by a chain 19 to prevent the pin from being lost.

In operation, mop material is secured to the mop head by the jaws 3, 3' and the operator grasps the handle 5'. He then rolls the mop along the floor on the rollers 20, and if the mop is moved along the base board, the mop material will brush or clean said base board.

From the foregoing, it is believed that the construction, operation and advantages of the invention may be readily understood, and I am aware that changes may be made in the details disclosed without departing from the spirit of the invention as expressed in the claims.

What I claim and desire to secure by Letters Patent is:

1. In a mop for base boards, a substan-

110

- substantially vertical plate forming a mop head, a stationary jaw arranged at one of the side edges of said plate, a movable jaw cooperating with the stationary jaw for holding mop material, rotary supporting means on the lower end of the plate to permit the latter to be readily moved along the floor while held in the substantially vertical position, and a handle connected to said plate.
- 10 2. A mop for base boards, comprising a head formed of a plate adapted to be vertically positioned when in operation, the vertical edges of the plate being shaped to form

rigid jaw members, spring pressed jaw members pivotally secured to the plate for cooperation with the rigid jaw members for holding mop material, a handle secured to the plate for moving the same, and anti-friction supporting means for the plate whereby it may be moved over a support in proximity to the base board for cleaning the latter.

In testimony whereof I have affixed my signature.

DURWARD M. ALLEN.
